UNITED STATES PATENT OFFICE.

HAROLD WILSON, OF NEW YORK, N. Y.

DESIGN FOR A PUZZLE-BOX.

SPECIFICATION forming part of Design No. 26,230, dated October 27, 1896.

Application filed August 17, 1896. Serial No. 603,088. Term of patent 3½ years.

To all whom it may concern:

Be it known that I, HAROLD WILSON, a citizen of the United States, residing at New York, in the county of New York and State of New York, have invented a new and Improved Design for a Puzzle-Box, of which the following is a specification.

My design consists of a new and useful configuration of a puzzle-box.

The box is open at the top and has a bottom and four rectangular sides. The space inclosed by the sides is divided by means of the parallel partitions 1 2 3, which terminate in the side of the box D into four parts a b c d, closed along the side D and open at the opposite end. Three of these parts a, b, and c are divided by partitions 4, 5, and 6 into smaller compartments, the partitions being parallel to those designated 1 2 3. The part d is divided by means of the partition 7, which is parallel to and of equal length with

the partition 6 and the several other partitions 8 9, which are parallel to 7 and 10, 11 and 12, which are at right angles thereto. Two of these divisions e and f are closed at 25 the ends. The other two, G and S, are open and communicate with each other.

The leading feature of my design is the straight parallel partitions forming passageways alternately open and closed at one end 30 and leading into two rectangular compartments which communicate with each other.

Having described my invention, what I claim is—

The design for a puzzle-box, substantially 35 as shown and described.

In testimony whereof I have hereunto set my hand the 14th day of August, 1896.

HAROLD WILSON.

In presence of—

JAS. B. KILSHEIMER,
WILLIAM R. BAIRD.
